UNITED STATES PATENT OFFICE

GASTON FRÉDÉRIC COURTOIS, OF LYON, FRANCE

ATOMIZER

Application filed April 15, 1929, Serial No. 355,077, and in Belgium April 26, 1928.

The present invention relates to atomizers. One of the objects of the invention is to produce an assembly capable of being quickly and easily assembled and cleaned.

5 Other objects will appear in the course of the detailed description now to be given with reference to the accompanying drawings, in which:—

Fig. 1 is an axial section through one illustrative embodiment of the invention;

10 Fig. 2 represents a section taken on line 2—2 of Fig. 1.

Referring to Figs. 1 and 2 of the drawings, there is shown a container *a*, topped by 15 a vaporizing assembly composed of a head *b* provided with passages b^{00} , b^{000} , b^{0000} , and d^0 ,—a pair of interengaging elements *e* and *h*, element *e* carrying a tube *f* having an orifice f^0 formed therein, and element *h* being provided with an orifice h^{10} in line with 20 f^0 ,—a liquid supply conduit *c*,—an air supply conduit *d* connected to a bulb or other source of compressed air (not shown),—and a cylindrical element *g* rigidly attached to 25 element *e* and serving to diminish the effective diameter of orifice f^0 , the use of this element being optional.

To assemble the device, element *g* is first 30 rigidly mounted inside element *e*, tube *f* is screwed into place, and elements *h* and assembly *e*, *f*, *g*, are inserted through opposite ends of the horizontal bore.

It will be noted that the head of element *g* 35 is provided with a boss in line with the axis thereof and that when interengaging elements *e* and *h* are screwed together, head *e* of the former takes up against said boss so as to rigidly fix element *g* in position.

In operation, compressed air, entering 40 through d^0 , will cause liquid to rise in conduit *c*, and fill the bore of tube *f*, the head of element *g* being flattened to permit communication between b^{0000} and the inside of tube *f*. At the same time compressed air will 45 pass through passages b^{00} , b^0 and h^{10} and vaporize the liquid exuding from orifice f^0 . The use of element *g* may be dispensed with, orifice f^0 , in that case, being reduced to limit the flow of liquid to the quantity desired. 50 The only advantage in including element *g*

is to permit the enlargement of orifice f^0 and so facilitate cleaning of the latter.

What I claim is:—

In combination, an atomizer head having a cylindrical bore therethrough, said atomizer head being provided with a pair of passages communicating with said bore and adapted to supply air and a liquid to the latter, and a pair of nozzle elements fitting into opposite ends of said bore and threadedly engaging with one another, one of said nozzle elements enclosing a portion of the other, each one of said nozzle elements having passages formed therein communicating with one of the passages in said atomizer, each of said nozzle elements having portions thereof abutting against one end of said bore when in assembled position. 55

In testimony whereof I have signed this specification.

GASTON FRÉDÉRIC COURTOIS.
